LUBRICATOR

Arthur E. Westburgh, Jamestown, N. Y., assignor
to Edward R. Haglund, Jamestown, N. Y.

Application July 10, 1933, Serial No. 679,768

15 Claims. (Cl. 184—103)

This invention relates to an automatic lubricator and the novel features insure maximum dependability and durability, flow of the oil in the correct quantity without gurgling and danger of foreign matter entering the oil or lubricant, and accessibility of the parts for inspection and cleaning.

A prime object is to provide a construction having a reservoir which may be readily displaced or tilted, without requiring detachment, for inspection or observation of the flow of lubricant.

Another aim is to provide novel adjustable valve means for the reservoir held open by and under control of novel closure means for the reservoir.

A further important feature is to provide a novel conduit for the feed of the oil from the reservoir to the cup constituting the attaching connection between the reservoir and pivoted closure of the oil cup. A removable strainer and a sediment sump within the reservoir coact with the conduit and the latter has a plurality of outlet passages terminating at different elevations within the oil cup to guard against gurgling of the oil and maintain a constant level of oil within the cup.

The more specific objects and advantages will become apparent from a consideration of the description following taken in connection with accompanying drawing illustrating an operative embodiment.

In said drawing:

Fig. 1 is an elevation of a motor equipped with a lubricator constructed in accordance with the invention;

Fig. 2 is an elevation of the lubricator alone, partly broken away to disclose details;

Fig. 3 is an elevation of the lubricator alone taken at 90° to Fig. 2;

Fig. 4 is a plan view of the lubricator, partly broken away to disclose a detail construction;

Fig. 5 is a central, vertical sectional view through the lubricator taken on the line 5—5 of Fig. 4;

Fig. 6 is a plan view of the reservoir with the closure and bail removed;

Fig. 7 is an elevation of the lubricator from the same side as Fig. 3 but showing the reservoir in tilted position;

Fig. 8 is a central vertical sectional view through the conduit;

Fig. 9 is a side elevation of the cylindrical strainer;

Fig. 10 is a fragmentary side elevation of the

lubricator, reverse to Fig. 2, primarily showing the hinge connection of the reservoir to the cup, and

Fig. 11 is a detail longitudinal sectional view through one of the outlet valves.

Referring specifically to the drawing wherein like reference characters designate like or corresponding parts, 10 designates an oil cup adapted for attachment to any desired part requiring lubrication, and for example, it is shown in Fig. 1 as connected to the bearing housing 11 of an electric motor 12, to lubricate the bearing and shaft 13 of the latter. Such oil cup may be secured in place by means of a screw threaded nipple 14, having an oil outlet passage 15 therethrough, or in any other desired manner. The chamber of said oil cup is normally covered by a closure plate 16 having an opening movement so that the chamber may be inspected, the feed of oil observed and sediment removed. Preferably said closure 16 and cup 10 have ears at 17 and 18, respectively, pivotally connected by a pintle 19 about which a coil spring 20 is disposed with one end abutting the closure and the other end abutting the reservoir, thus furnishing a spring hinge constantly urging the closure 16 to closed position.

Said closure 16 carries an oil reservoir 21, preferably metallic, having a glass or other transparent window 22 secured over a sight opening 23 in any suitable manner as by means of clips and leak-proofing cement at 24.

A central threaded opening 25 is provided in the bottom of reservoir 21 and a conduit member 26, by means of external screw threads 27, is screwed thereinto. Such threads 27 also engage those in a central screw threaded opening 28 in the closure 16, whereby the conduit constitutes a connecting means between the reservoir and oil cup. Lock nuts 29, preferably externally knurled, engage the threads 27 below the closure 16.

Reverting to the conduit 26, it preferably has a plurality of bores or passages 30 for travel of the oil from the reservoir to the oil cup and in each passage, a valve 31 of any preferred construction is disposed. As shown best in Fig. 11, each valve may have a casing 32 removably screw threaded at 33 in the upper ends of such passages. Slidable in spiders 34 in such passages are valve stems 35 carrying heads 36 at their lower ends urged toward closing engagement with the lower ends of the casing by expansive coil springs 37 about the stems, resting on the

105

110

spiders 34 and engaging abutments 38 at the upper ends of the stems.

The aforesaid reservoir 21 has a removable closure 39 consisting of a cover member 40, a gasket 41 and a disk 42 secured rigidly together by a press-fitted rivet end 43 of a stud 44. Gasket 41 is usually of rubber, leather or the like and rests on the upper edge of the reservoir while disk 42 extends into the latter. A controller 45 to determine the extent of opening of the valves 31 and to maintain them open in operation, engages abutments 38 and has a shank 46 screw threaded at 47 in the stud 44. The extent of opening of the valves is controlled through the adjustment of said controller and the latter is held in adjusted positions against accidental slippage by the frictional pressure of a spring finger 48 against its threads, such finger being of spring metal and mounted by insertion through an opening 49 in the stud and upsetting of a terminal 49' of the finger.

Attention is called to the fact that the lower end of conduit 26 is bevelled or chamfered at 50 as a result of which the lower end of one oil passage 30 is below that of the other. The oil level in the cup is maintained constant and as high as the outlet of the other passage, air enters from the cup through the shorter passage, resulting in the flow of the oil into the cup 10 without gurgling. Said chamfer 50 is for the second purpose of enabling the conduit 26 to extend as low as practical in the oil cup and yet be capable of swinging out of the same when the closure 16 and reservoir 21 are swung as shown in Fig. 7.

A resilient bail 51 clamps the closure 39 on the reservoir, having terminals 52 removably pivoted in recesses 53 in the sides of the reservoir, a handle 54, hold-down portions 55 and gathered portions 56 to facilitate expansion and contraction. Said portions 55 are adapted to snap into depressions 57 of a pair of cam ribs 58 on the cover member 40.

To insure proper positioning of the closure 39 preparatory to clamping movement of the bail to engage the same, cover member 42 has a recess 58' adapted to receive a lug 59 at the upper inner edge of the reservoir, and cover 39 has a lug 60 to align with the sight opening 23.

A cylindrical open-ended oil strainer 61 of metallic wire screen for example, is removably partly telescoped over a reduced upper end of conduit 26 resting on a shoulder 62 thereof and extending into a recess or sump 63 in the bottom wall of the reservoir which accommodates the sediment.

Normally oil is maintained in the cup 10 to a level equal to that of the upper portion of the discharge end of passage 30 at chamfer 50 and when it recedes through use below that level, air enters through such passage from the oil cup and oil again flows into the cup to the said predetermined level. The flow is also under control of the adjustable valves 31 and when closure 39 is removed, such valves automatically close under action of their springs 37, thus being closed during the filling of the reservoir. The reservoir may be tilted when desired for cleaning or inspection, especially to check up on the correct flow of oil through the passages, as shown in Fig. 7. All of the parts within the reservoir are accessible for ready inspection and cleaning upon lowering of bail 51 and removal of closure 39. The strainer 61 is readily slipped off of reduced portion 62 for cleaning and the

sump 63 aids in draining sediment from the screen and permitting removal thereof.

Various changes may be resorted to provided they fall within the spirit and scope of the invention.

I claim as my invention:

1. A lubricator having a cup, a closure pivoted thereon for movement to an open position, a valved conduit screw-threaded to the closure and communicating with the cup, a reservoir screw-threaded on the conduit to supply lubricant therethrough and filling means for the reservoir independently of said conduit.

2. A lubricator having a cup, a closure pivoted for movement to an open position, a conduit connected to the closure having two passages communicating with the cup, and a reservoir carried by the conduit to supply lubricant therethrough, one of said passages terminating below the other passage.

3. A lubricator according to claim 2 wherein said conduit extends below the closure and has a chamfer across the lower extremity of one passage enabling the conduit to be swung out of the cup.

4. A lubricator having a cup, a closure pivoted thereon, a reservoir, a conduit member attaching the reservoir to the closure and extending below the same into the cup, the lower end of said member having a chamfered portion enabling the member to be swung out of the cup, said chamfered portion extending across a passageway through the conduit.

5. A lubricator having a cup, a closure pivoted thereon, a conduit having two passages therethrough, screw threaded to the closure and extending below the same, said conduit having a chamfer across one of said passages arranging the outlet of one passage below that of the other and enabling the conduit to be swung with the closure to the exterior of the cup, a reservoir threaded on the conduit, outlet valve means for said passages, one of the passages constituting a vent, a closure for the reservoir, means to secure the closure in closed position, and a controller carried by the closure and engaging the valve means to maintain the latter open when the reservoir is closed.

6. A lubricator according to claim 5 wherein the upper end of the conduit is reduced and the reservoir bottom has a sump about the same, and a cylindrical strainer telescoped over said reduced portion and extending into the sump.

7. A lubricator having a cup, a reservoir, means pivoting the reservoir on the cup for movement to an open position, conduit means exposed at its lower end through the said movement provided with two passages communicating with the cup and leading from said reservoir, valve means for said passages, closure means for the reservoir normally maintaining said valves open, and means to close the valves upon displacement of said closure means.

8. A lubricator having a cup, a closure pivoted on said cup movable to an open position to expose the interior of the cup, a reservoir on said closure movable therewith, conduit means for the passage of lubricant from said reservoir to said cup attaching the reservoir directly to said closure and extending beyond the closure into the cup, said reservoir having a filling opening independently of said conduit means, a closure for said filling opening, valve means for the conduit means completely above the lower end of the conduit means, means to urge the

150

valve means to position closing said conduit means against the entrance and discharge of lubricant, and means carried by said closure functioning in the closed position of the latter 5 to maintain said valve means open.

9. A lubricator having a cup, a closure pivoted thereon for movement to an open position, a conduit having external screw threads engaging the closure, a reservoir attached to 10 said screw threads, valve means in the conduit to control the passage of lubricant from the reservoir through the conduit, and filling means for the reservoir independently of the conduit.

10. A lubricator having a reservoir, an outlet 15 conduit extending therefrom for attachment to means to be lubricated, an outlet valve for said conduit normally urged toward closed position, said conduit having a reduced portion at its upper end, the bottom of said reservoir having a 20 sump about said reduced portion, a screen of cylindrical form telescoped about said reduced portion and extending into the sump, and a controller carried by the closure and engaging the valve in the closed position of the closure 25 to maintain the valve open.

11. A lubricator having a reservoir, an outlet conduit member in direct communication with the interior of the reservoir and extending therefrom, outlet valve means in the conduit of said 30 conduit member, said valve means in closed position completely preventing discharge through said conduit, a closure for the reservoir controlling the opening and closing of said valve means, means for attachment to a device to be 35 lubricated, and said last mentioned means mounting the reservoir and conduit member for movement to a position to observe the discharge end of the conduit.

12. A lubricator according to claim 11 wherein 40 said closure carries a part to directly control the opening and closing of said valve means, and means adjustably securing said part on the closure.

13. A lubricator having a reservoir, an outlet 45 conduit member in direct communication with

the interior of the reservoir and extending therefrom for attachment to means to be lubricated, an outlet valve in the conduit of said conduit member and normally urged to closed position, said outlet valve completely preventing discharge 80 through said conduit in closed position, a closure plate for the reservoir, a controller member, said controller member engaging the valve in the closed position of the closure plate to maintain the valve open, a disk of less diameter than the closure plate, a gasket between the closure plate and disk, a fastening means passing through the closure plate, gasket and disk, and said fastening means having screw threads 85 engaged by the controller member.

14. A lubricator having a reservoir, an outlet conduit member in direct communication with the interior of the reservoir and extending therefrom for attachment to means to be lubricated, an outlet valve in the conduit of said conduit member and normally urged to closed position, said outlet valve completely preventing discharge 90 through said conduit in closed position, a closure means for the reservoir, a controller member, means adjustably securing the controller member to the closure means, said controller member engaging the valve in the closed position of the closure means to maintain the valve open, said conduit member having a reduced portion at its upper end, said reservoir 95 having a bottom provided with a sump about said reduced portion, and a screen of cylindrical form telescoped about said reduced portion and extending into the sump.

15. A lubricator having a reservoir, a closure 110 plate resting on the upper edge thereof, a disk extending into the reservoir, a gasket between the plate and disk engaging said edge, outlet means for the reservoir including a valve, securing means extending through said plate, 115 gasket and disk, and a control member governing the extent of opening of said valve, said control member being mounted by the securing means.
